UNITED STATES PATENT OFFICE.

ADAM HEBERER, OF ALAMEDA, CALIFORNIA.

STEAM-BOILER.

SPECIFICATION forming part of Letters Patent No. 465,929, dated December 29, 1891.

Application filed March 6, 1889. Serial No. 302,168. (No model.)

To all whom it may concern:

Be it known that I, ADAM HEBERER, a citizen of the United States, residing in Alameda, in the county of Alameda and State of California, have invented certain new and useful Improvements in Steam-Boilers, of which the following is a specification:

The improvements embraced in this invention relate more particularly to portable steam-boilers of the upright kind; and the invention has for its object the production of a light, compact, and rapidly-generating boiler in parts or sections of convenient size and weight to be readily handled and transported, and so arranged and fitted together also as to be easily set up for use without the aid of specially-skilled workmen.

The improvements include certain novel construction and combination of inner and outer shells, with water-tubes and partitions, as hereinafter explained, constituting the boiler proper.

The following description explains the nature of these improvements and the manner in which I have constructed, produced, and applied them in carrying out my said invention, reference being had to the accompanying drawings, that form part of this specification.

Figure 1 of the drawings is a vertical section taken transversely through the boiler and fire-box. Fig. 2 is a side elevation taken from the right-hand side of the boiler, with a portion of the outer shell broken away and the exposed part of the inner shell and circulating-tubes shown in section. Fig. 3 is a top view of the fire-box, and Fig. 4 is a vertical section taken in a longitudinal direction through the center of the fire-box. In these two last-mentioned views the base of the boiler is shown in section.

Similar letters of reference in the several figures of the drawings indicate corresponding parts.

Both the inner and the outer shells of this boiler are formed of tubular sections with flanged joints that may be permanently fastened by riveting; or where the boiler is to be set up in a locality not readily accessible or the means of transportation are limited the

sections may be made of convenient size for handling and the joints may be fastened by bolts and nuts. Boilers of the smaller sizes can be made of wrought-iron tubes, to the ends of which the flanges for the joints are fixed by riveting. The annular space between the two shells forms the water-room at the lower part of the boiler, and above this the steam-space, which last-named part is divided by partitions running both perpendicularly and horizontally, to produce a circuitous route or passage for the steam from the lower part to the upper part of this space, where the steam outlet is to be located.

The heads of the boiler are cast-metal plates, with circular grooves to receive the ends of the two shells and with central apertures for the fire and products from the furnace upon which the boiler stands. The two heads are drawn together and held by a number of long bolts or rods with threaded ends for nuts, extending from one head to the other through the space between the two shells. A stack or chimney is fixed over the center opening in the top plate, and the similar opening in the base-plate registers with an aperture of the same size in the top of the furnace, the location of which aperture is somewhat to the rear of the middle portion of the furnace-top. The outer shell is cylindrical and substantially of the same diameter from top to bottom; but the inner shell is flattened on two opposite sides for the full length of the shell, or for as much of the length as the tubes are placed. These flattened sides are parallel, and they constitute the tube-sheets, between which the tubes are set in close order horizontally across the fire-space. This form of shell and arrangement of tubes afford suitable degree of strength and a large amount of heating-surface, besides giving facilities for cleaning and repairing in those cases of construction where the outer shell can be taken apart.

The base-plate of the boiler has a wide flange to bolt down upon the top plate of the furnace, and through the bottom is carried the blow-off aperture, although this outlet may quite as well be located in the side of the outer shell above the base-plate.

The furnace is formed of a sheet-metal body

and a cast-metal front plate inclosing the fire-box of bricks or tiles, in the top of which the fire-aperture is carried up through the outside sheet-metal top. Between the fire-box 5 and the surrounding walls an air-space is left not only beneath the grate-bars for an ash-pit, but at the top, sides, and rear end of the furnace for air-heating spaces and also to receive a water-heating coil of pipe.

10 Air is taken in through numerous small apertures provided in the top plate of the furnace, and by closing all other draft-openings after the fire is well under way the air for combustion will be raised in temperature 15 to a considerable degree before entering the fire-box.

The water-heating coil is fixed in place between the sides of the fire-box and the surrounding furnace-body, with its ends leading outside and furnished with couplings for connecting the water-supply pipe to one end and the feed-pipe of the boiler to the other end.

18 The grate-bars and the fire-box are supported by transverse bars or beams having their ends carried by ledges or projections on the inner sides of the furnace-plates. These supports also take the water-heating coil.

25 In the the several figures of the drawings, 30 A A are the sections that form the outer shell of the boiler.

B B are the sections of the inner shell, and B' B' the flattened sides, in which the ends of the tubes C C are fixed.

35 D D' are the flange-joints of the inner and outer shells respectively.

E E are perpendicular partition-plates extending from the top of the steam-space down to a point below the water-line and dividing 40 the space in two parts, that are in communication with each other through the tubes.

45 F F are the horizontal partitions that divide these spaces on either side of the upright partitions and produce a circuitous passage through the steam-space from the water-line up to the steam-outlet G at the top.

H I are the two plates that form the heads of the boiler, and K K are the long bolts holding the heads in place.

50 h h i i are the annular grooves in which the ends of the boiler-shells are set, and H^x I^x are the center apertures for the fire. The top plate has the smoke-stack L fixed over this opening, while the brick-work of the fire-box 55 is carried up through the top plate of the furnace to take the base-plate H, the opening H^x of which corresponds with the form of the lower end of the inner shell, as shown in the sectional view, Fig. 3.

60 M M are the walls of the fire-box, and N are the grate-bars.

P is the front plate of the furnace, having fuel and draft openings furnished with the necessary doors, and R S are the top plates, 65 side plates, and back plate forming the body

of the furnace and inclosing the fire-box. A bottom plate R^x may be added to complete the metal body, or the side plates may be set directly on a brick foundation, that will form the bottom of the ash-pit.

70 T is the air-heating space around the fire-box, and T^x T^x are the air-inlet apertures in the top plate of the furnace.

U is the water-heating coil, and V V are the supports for the bricks or tiles of the fire-box and for the grate-bars.

75 Connection for the water-supply pipe with the heater is seen at W, Figs. 1 and 3, and for the feed-pipe of the boiler with the heater at Y outside the furnace. The necessary gages, 80 cocks, and valves are also provided, and a blow-off Z at the bottom of the water-space is carried to the outside and furnished with a suitable cock. All the joints can be thoroughly packed.

85 As thus constructed it will be seen that the parts can be made of convenient size for ready transportation in an unsettled country and are easily set up and put together by a person of ordinary skill. In addition to these 90 features the boiler has great heating capacity, is free from danger of exploding, can be readily repaired and kept in order, and will be found to possess considerable economy in the use of fuel.

95 Having thus fully described my invention, what I claim, and desire to secure by Letters Patent, is—

1. The herein-described boiler having an annular steam-generating space and central fire-space and consisting of an outer cylindrical shell, an inner shell with flattened sides and horizontally-disposed tubes, the heads with grooves to take the ends of the outer and inner shells, central apertures for passage of the fire and products of combustion, and the long bolts or rods taking through both heads, as herein set forth.

2. The combination of outer-shell sections, with flange-joints, the inner-shell sections having flattened sides and horizontally-disposed tubes, with flange-joints to unite one section to the other, the heads which are adapted to take the ends of the inner and outer shells, and long bolts or fastenings that draw the two heads into place, substantially as described.

3. In an upright boiler, the combination of outer shell A, inner shell B, with horizontally-disposed circulating-tubes C C, and the perpendicular and horizontal partitions E F, dividing the annular steam-space, as described.

4. In an upright boiler of the kind described, the combination of an inner and an outer shell producing an annular steam-generating space, horizontally-disposed generating-tubes extending through the inner shell across the fire-space, and vertical partitions set opposite to each other and dividing the steam-generating space, as set forth.

5. In an upright boiler having a central fire-space, the combination of an outer and an inner shell, tubes extending across the fire-space and passing through the inner shell, and horizontal partitions between said outer and inner shells, as and for the purpose set forth.

In testimony that I claim the foregoing I have hereunto set my hand and seal.

ADAM HEBERER. [L. S.]
